Inventor:
Calvin E. Strout
by S. M. Bates *Atty.*

UNITED STATES PATENT OFFICE.

CALVIN E. STROUT, OF PORTLAND, MAINE.

CABLE CHAIR.

Application filed October 21, 1921. Serial No. 509,450.

To all whom it may concern:

Be it known that I, CALVIN E. STROUT, a citizen of the United States, residing at Portland, in the county of Cumberland and 5 State of Maine, have invented certain new and useful Improvements in Cable Chairs, of which the following is a specification.

My invention relates to a trolley supported chair for telephone or other line men 10 where wires are to be strung on a pair of cables one above the other.

This rolling chair is designed to be suspended by both the upper and lower cables and to run freely over the rings or hooks 15 through which the telephone wire cables are drawn.

Under the old system of stringing telephone wires the line men made use of a trolley supported chair which was adapted 20 to run on a single cable only so that it was not adapted to cases where the supporting cables were two in number one above the other with telephone wire cables hung to each.

According to my invention, I make use of 25 a seat member which is substantially a flat board or plank with a frame at each end for supporting the seat member on the two supporting cables.

Each frame has journalled to it a lower 30 grooved pulley resting on a lower supporting cable and an upper grooved pulley resting on the upper cable.

In practice, I construct these frames with 35 an opening on one side to admit the upper cable so that the chair may be put in position by simply hooking it over the upper cable.

I have illustrated my invention by means 40 of the accompanying drawing in which:

Fig. 1 is a plan of my device,

Fig. 2 is a side elevation, showing the 45 chair in position on the two cables and,

Fig. 3 is an end elevation.

An elongated seat member 1 forms the 50 foundation of the device and this consists of a plank or board having its lateral edges chamfered so that a man can sit on the board with his legs overhanging. At each 55 end of the seat member 1 is a supporting frame preferably formed of metal strips bolted to the seat member.

As here shown, the frame consists of an 60 upright strip 3 bolted near the end of the

seat with a reinforcing strip 4 forming an 55 offset at the lower end and also bolted to the seat and forming an open space with the strip 3 for the lower truck 5 running on the lower cable 6. The truck 5 is journalled between the strips 3 and 4 by a suitable pin 60 or axle. A suitable slot is formed in the seat to allow the truck 5 to project through and to bring the seat some distance above the lower cable. The strip 3 extends upward to a point somewhat above the upper cable 65 where it turns downward upon itself enclosing the upper truck 7 which is journalled to the two sides of the strap. The extreme end of the strap forms a terminal 8 bent to leave an open space by which the device can 70 be hooked over the upper cable 9. The central portion of the strip 3 is bent outward to form a lateral stiffening projection 10. The structure is stiffened by a brace 11 secured to the seat near the lower truck 5. 75 The brace extending upward to the top of the frame being riveted at the top and also to the projection 10 at an intermediate point. This construction of the frame makes a 80 vertically rigid structure with an open side adapting it to be hooked over the upper cable and sufficiently rigid to hold the seat.

The device is pushed along the cable, the trucks overrunning the hooks or rings 12 through which the telephone wire cables 85 are threaded.

It is immaterial whether both cables are subjected to an equal tension or not. If one of the cables is slack the tighter one will be sufficient to hold the chair in place. 90

The chair may if desired be used on a single cable by using the upper trucks alone.

I claim:

A trolley chair for telephone or other line men consisting of a flat elongated seat, a 95 suspending frame secured to each end of said seat, said frame being composed of an upright strap secured to the seat, the lower end having an offset for enclosing and journalling the lower truck, the upper end of the frame being bent over to enclose and form a journal recess for the upper truck, the central portion being swelled or bent outward to form a stiffening projection and the strip terminating in a lateral hook, a 100 brace secured to the bottom and to the top and to said stiffening projection.

CALVIN E. STROUT.
